COMBINED CONTACT LENS INSERTER AND APPLICATOR

Abraham Toran, 620 Pearl St., Oceanside, N.Y.

Filed Oct. 22, 1965, Ser. No. 87,739

Term of patent 14 years

(Cl. D57—1)

FIG.1

FIG.4

FIG. 1 is a front perspective view of the combined contact lens inserter and applicator showing my new design.

FIG. 2 is a rear elevational view of the invention.

FIG. 3 is a side elevational view showing my new design.

FIG. 4 is a bottom elevational view thereof.

I claim:

The ornamental design for a combined contact lens inserter and applicator, as shown.
